UNITED STATES PATENT OFFICE.

CHARLES B. HATFIELD, OF TROY, NEW YORK, ASSIGNOR TO NATHAN D. DODGE, OF NEWBURYPORT, MASSACHUSETTS.

DESIGN FOR A SHOE OR SLIPPER.

SPECIFICATION forming part of Design No. 14,901, dated March 25, 1884.

Application filed December 29, 1883. Term of patent 14 years.

To all whom it may concern:

Be it known that I, CHARLES B. HATFIELD, of Troy, county of Rensselaer, and State of New York, have invented and produced an original Design for Shoes and Slippers, of which the following is a full, clear, and exact description.

Reference is to be had to the accompanying drawing, forming a part of this specification, in which a perspective view of my newly-designed shoe is shown.

Heretofore the upper edges of shoes and slippers have been made straight, curved, or scalloped. In my newly-designed shoe the upper edge is provided with angular offsets. The offsets on the tongue incline toward the sides of the shoe. The offsets can be made at right angles, or obtuse or acute angles, to the upper edge of the shoe.

The same design can also be applied to slippers.

Some shoes are provided with two side straps, C, at the front of the opening, and in my newly-designed shoe the ends of the said straps are beveled or cut to form angular figures, which may have more or less angles.

Having thus described my design, I claim as new and desire to secure by Letters Patent—

1. The design herein described for shoes or slippers, consisting of angular offsets at the heel, angular-ended straps C, and the tongue B, also having beveled or angular ends, as shown.

2. In a design for a shoe or slipper, the angular offsets at the heel portion of the upper edge of the shoe or slipper, the said offsets inclining downwardly from the upper edge of the heel portion to the approximately straight upper edge of the side portions of the shoe or slipper, as shown.

3. In a design for a shoe or slipper, the strap C, the end of which has the shape and configuration of a polygonal figure, as shown.

4. In a design for shoes or slippers, the heel portion having angular offsets, approximately straight lines from said offsets to the straps, and angular offsets at the base of said straps, as shown.

CHARLES B. HATFIELD.
